H. C. JOHNSON Inventor

By Richard B. Clegg, Attorney

UNITED STATES PATENT OFFICE.

HARRY C. JOHNSON, OF MASON CITY, NEBRASKA.

AUTOMATIC STACKER-TOOTH POINT.

Application filed May 16, 1924. Serial No. 713,819.

To all whom it may concern:

Be it known that I, HARRY C. JOHNSON, a citizen of the United States, residing at Mason City, in the county of Custer and State of Nebraska, have invented certain new and useful Improvements in Automatic Stackr-Tooth Points, of which the following is a specification.

This invention relates to a point for a stacker tooth which will allow the hay or like to pass readily upon the fork and prevent the same from backing off from the fork with the buck.

The device contemplates the provision of a very simple and efficient construction which is reliable in operation, inexpensive to manufacture, strong, durable, and well adapted to the purpose for which it is designed.

This body embodies a pivoted retaining member which will be disposed in a substantially reclining position when the hay is being forced on the fork but which will move to a standing position when the load is bucked upon the fork. It is a common practice to use a spring finger or an integral finger. Both of these structures have numerous objections which are overcome by this invention.

With the above and numerous other objects in view as will appear as the description progresses, the invention resides in certain novel features of construction, and in the combination and arrangement of parts as will be hereinafter more fully described and claimed.

In the drawing:

Figure 1 is a perspective view of the point showing the same on a stacker tooth,

Figure 2 is a longitudinal section therethrough,

Figure 3 is a fragmentary bottom plan view of the point, and

Figure 4 is a transverse section taken through the point substantially on the line 4-4 of Figure 2 looking in the direction of the arrow.

Referring to the drawing in detail it will be seen that 1 designates an ordinary stacker tooth having a beveled end 2. My point is in the form of a hollow shell, one end beveled and closed at 3 so as to termi-

nate in the point 4. The other end is opened so as to receive the beveled end of the stacker tooth which is held in place by a pin or other suitable means 5. The shell is provided with an elongated longitudinally extending upper slot 6 and a substantially shorter slot 7 registering with the forward end thereof. It is to be noted that the extremity 8 of the stacker tooth 1 terminates at the rear or inner edge of the bottom slot 7.

A retaining finger 10 is pivoted intermediate its ends as at 11 within the shell of the point so that its upper portion extends through the slot 6 and its lower portion extends into but not beyond the slot 7. The upper or longer portion of this finger is provided with the beveled end 12 so that the hay may readily pass thereover when the finger is in the reclining position that is resting on the beveled portion 2 of the tooth 1. When the load on the fork is bucked this finger will move to the dotted line position shown in Figure 1 and is substantially vertical so that its upper portion engages the forward end 14 of the slot 6 while its lower or shorter end engages the end 9 of slot 7 and thus all of the strain is taken off of the pivot pin 11.

Although I have described the invention with a certain degree of particularity, it is to be understood that changes in the details of construction may be resorted to without departing from the spirit or scope of the invention as hereinafter claimed or sacrificing any of its advantages.

Having thus described my invention, what I claim as new is:

1. In combination with a stacker tooth having a beveled end, of a point shell disposed on said bevel end, said shell being of hollow construction having an elongated upper slot and a substantially short lower slot, and a retaining finger pivoted in the shell and extended through the elongated upper slot so that it may be disposed either in a vertical position or reclining on the beveled end of the stacker tooth.

2. In combination with a stacker tooth having a beveled end, of a point shell disposed on the beveled end of the stacker tooth and being of hollow construction pro-

vided with an upper elongated slot and a lower relatively short slot, the inner end of said short slot terminating adjacent the extremity of the stacker tooth, and a retaining finger pivoted intermediate its end within the shell so that when vertically disposed it abuts the forward end of the elongated slot and the rear end of the short slot and when

reclining substantially rests on the beveled end of the tooth.

In testimony whereof I affix my signature in presence of two witnesses.

HARRY C. JOHNSON.
